PLASTER ROLL PACKAGE

Filed Jan. 18, 1928

Inventor
ROBERT P. HAYDEN.

By *Jack Richmond*

Attorney

UNITED STATES PATENT OFFICE

ROBERT P. HAYDEN, OF NEW BRUNSWICK, NEW JERSEY, ASSIGNOR TO JOHNSON & JOHNSON, OF NEW BRUNSWICK, NEW JERSEY, A CORPORATION OF NEW JERSEY

PLASTER-ROLL PACKAGE

Application filed January 18, 1928. Serial No. 247,663.

The invention is a packer carton for adhesive plaster and was devised to overcome certain disadvantageous features of standard shipping cartons.

5 Adhesive plaster generally is supplied to hospitals in the form of rolls made up of single or multiple units mounted on a hollow core which latter is intended to cooperate with hospital furniture such as a roll stand having 10 a rod or mandrel to receive the core.

The problem is to provide for shipping rolls of adhesive plaster so that they will not be damaged to such extent in transit that they cannot successfully be mounted on the 15 roll stand and so that they will properly be ventilated and thus kept over long periods without deteriorating.

The object of the invention is the solution of this problem and in such way as not 20 appreciably to affect the price of the plaster.

The nature, characteristic features, and scope of the invention will more readily be understood from the following description taken in connection with the accompanying 25 drawings which are illustrative of the preferred embodiment.

In said drawings,

Figure 1 is a perspective view of a shipping appliance embodying the invention.

30 Fig. 2 is a sectional elevational view with parts broken away.

According to my inventive thought, provision is made so that the roll of plaster, whether of the single or multiple unit type, is floated or free to rotate with relation to the carton, whereby it is safeguarded against damage which, otherwise, would follow sharp blows or the imposition of weight or pressure. In another aspect, the invention contemplates the provision of a cool dark environment to the end of preserving the physical 40 qualities of the plaster.

In the drawings, the numeral 5 represents 45 generally a roll of plaster consisting of separate plaster units of variable or graduated width mounted on a common axis. The latter is a hollow core 6 of fiber or metal. It is shown as having ventilating passages 7, 50 which communicate with the clear through

the open heads of the core and thus provide for free circulation of air.

The packer carton comprises telescopic tube sections 8 of somewhat greater diameter than the plaster roll in order to insure the necessary spacing or clearance for air circulation and for relative movement of the roll. For simplicity and to lessen cost, the cylindrical walls of the sections 8 are formed of fiber; the ends being fortified against collapsing by the provision of stiff metal or other refractory heads 9.

The roll of plaster units is supported relatively to the carton in such way as to provide for full clearance and adequate ventilation. This preferably is accomplished by the provision of means of centering, or of rotation on its own axis, of the plaster roll. For example, the heads 9 have central apertures fitted with inverted spuds or thimbles 10 designed to engage the respective ends of the core 6 and thereby constitute centering devices or journals for the plaster roll. Under such construction, arrangement and assembly, the roll has clearance on all sides, and being 70 free to rotate on its own axis is enabled to oppose yielding resistance to and thus withstand blows or forces which ordinarily would seriously damage the roll or its core.

Adequate ventilation is established through 75 the medium of the axial openings 11, provided in the heads 9.

Having described my invention, I claim:

1. A package comprising a roll of plaster consisting of co-axially supported variable 80 widths of plaster, a hollow core constituting such support and having ventilating apertures throughout its length, and a packer carton comprising carton sections having heads equipped with means adapted to penetrate the ends of the core to provide for rotary support of the roll.

2. A package comprising a roll of plaster consisting of co-axially supported variable 85 widths of plaster, a hollow core forming a common support for the plaster units and having ventilating apertures throughout its length, a packer carton consisting of detachable sections, and heads for said sections having central inward depressions forming 90 100

bosses which penetrate the ends of the core and so float the roll with relation to the carton, said bosses having passages for venting the carton, substantially as described.

5 3. A package comprising a plurality of rolls of surgical adhesive plaster, a foraminous core constituting a coaxial support for said rolls, a packer carton comprising headed telescopically fitted tubular sections, and
10 thimbles secured to the heads and affording trunnion mountings for the core whereby the latter is free to rotate and to support the plaster rolls with clearance with respect to the carton, said thimbles adapted to supply
15 air to the core for ventilating purposes.

4. A package comprising a roll of surgical adhesive plaster, an open ended perforated core on which the plaster is rolled, and a packer carton comprising interfitting mated
20 carton sections having clearance with respect to the roll and whose heads are equipped with devices for rotatably supporting the core and for admitting air thereto for ventilating purposes.

25 In testimony whereof I affix my signature.
ROBERT P. HAYDEN.
